UNITED STATES PATENT OFFICE.

WILLIAM J. DURING, OF SYRACUSE, NEW YORK, ASSIGNOR TO PRECISION CASTINGS COMPANY INC., OF FAYETTEVILLE, NEW YORK, A CORPORATION OF NEW YORK.

DIE CASTING AND METHOD OF PRODUCING SAME.

Application filed November 17, 1925. Serial No. 69,604.

This invention relates to certain new and useful improvements in die-castings and the method of producing die-castings.

Heretofore it has been customary to form die-castings and die-cast articles of a solid body of some metal or alloy suitable for die-casting. Such articles are comparatively heavy and the metal is relatively expensive.

I have discovered that altho the metal is shot into the die under high pressure and at a very high temperature, for instance 900 deg. centigrade, or higher, that it is possible to support a core or cores of wood within the die in such a manner that a shell of metal of desired thickness will be cast around it so as to fill the space within the die outside the core, without the wooden core being consumed or appreciably affected altho under ordinary circumstances molten metal at such high temperatures would be destructive of the core. This result is accomplished doubtless by reason of the fact that the application of the metal coating to the wooden core is so instantaneous and with practical absence of sufficient oxygen to sustain combustion and cooling of the metal is so rapid that the wooden core is practically unaffected, except perhaps for a slight charring upon the exterior surface.

In fact, the grain of the wood seems to be imprinted on the inner surface of the metal shell as a result of the extremely close association of the metal and the wooden core, and the metal seems to enter the pores of the wood resulting in a substantial adhesion or cohesion of the same substances.

The product is greatly improved in that it is much lighter than a solid metal product and further, and perhaps more important, a substantial saving in metal is effected, and thereby a saving in cost as the wooden insert is considerably less expensive than the metal which it displaces.

Further, for many purposes the wooden insert has advantages, as for instance when it is desired to secure other parts to the die-casting.

Further, the wooden core lends itself to the production of certain die-cast articles of required strength that could be produced with great difficulty, if at all, by the usual die-casting process.

In the drawings:

Figure 1 illustrates a section of a die having a wooden insert supported therein. 55

Figure 2 is a section on line 2—2, Figure 1.

Figure 3 illustrates a particular die-cast article as produced by the apparatus of Figures 1 and 2.

Figure 4 illustrates a die for forming a somewhat different die-cast article including an enclosed wooden core. 60

Figure 5 illustrates the article produced by the apparatus of Figure 4.

The die-cast article shown in Figure 3 is 65 designed for such a use, as for instance adapted to constitute a portion of a vacuum cleaner, that eye-members —1— are required at its opposite ends. It is practically impossible to die-cast such a completed article by present methods which shall have the required 70 strength.

The method of this application among other advantages, is peculiarly adapted for such production, and the same may be carried out as follows:— 75

It is important that the wooden core be thoroughly dried and practically all the moisture be removed therefrom so that little if any shrinkage will result when the product is completed. A dry wooden core —2— of desired shape is formed and ordinary screw-eyes —3— are threaded into its opposite ends so that the eyes project from the wooden core. The die —3— is here formed 80 with recesses outside the chamber in which the casting is to be formed for receiving these eyes, and the eyes may be supported as illustrated in Figures 1 and 2 upon pins —5— carried by the die and extending into 85 the recesses for receiving the eyes —1—. In this manner the wooden insert —2— is supported within the die-chamber. The molten die casting metal such as an alloy consisting of approximately 92 parts of aluminum, ap-

proximately 5 parts of nickel and approximately 3 parts of copper is then shot into the die which is of sectional character held together in any suitable way and instantaneously forms itself as a coating upon the 90 outer surface of the wooden insert —2—, and attaches itself to the shank portions of the screw eyes —3— that are positioned in the die-chamber, the eyes 1—1 being them-

selves protected by location in recesses in the dies formed to receive them.

The result is a product of very substantial character composed of a wooden core 5 enclosed by a layer of die-cast metal of a thickness determined by the space between the core and the wall of the die-chamber.

The eyes —3— being formed of rolled or drawn steel, such as steel wire and having 10 their threaded ends screwed into the wooden insert and their shanks surrounded by and secured to the enclosing layer of die-cast metal, provide a much stronger and more substantial structure than if the whole article were formed of die-cast metal, even were 15 that practical.

The invention has many adaptations, as for instance in the die-casting of knobs or handles for various uses. For illustration, 20 the knob of a transmission lever, as shown in Fig. 5, the method of manufacture of which is illustrated in Figure 4.

Suitable dies having been formed, a dry piece of wood —8— for this purpose perhaps preferably of spherical shape is inserted within the die. This wooden core is formed with a cylindrical recess —10— which receives the reduced cylindrical end of a stud —9— fitting the recess, whereby the 25 core is supported within the die. The enlarged portion of the stud contacts with the core —8— and extends outwardly through the enclosing space and the die. By this means the core is effectively supported and 30 a cylindrical recess is formed within the completed article which adapts itself for ready attachment to various articles. The enlarged portion of the shank —9— that extends outwardly through the enclosing space 35 within the die forms a circular opening —11— in the enclosing spherical casing —12— of die-cast metal and for the particular purpose that this article is designed, the opening —11— is of somewhat greater diameter than the recess —10—, but obviously this 40 is variable at will in the production of a desired form and shape of article. With the core supported as illustrated in Figure 4, the metal is shot into the die and forms around 45 the wooden core —8— a spherical casing of die-cast metal of desired thickness, which in 50

this illustration is broken only by the opening —11—.

It will be obvious that the core —8— may be of any desired size so that the enclosing 55 layer of die-cast metal may be of desired thickness.

Altho I have shown and described specific articles and specific methods of their manufacture, it will be obvious that this method 60 adapts itself to the production of various articles of many and varied forms and shapes, and I do not desire to limit myself to any particular method of their manufacture or to any particular articles or forms of 65 the same, or thickness of the layer of metal cast about the core, except as the same may be specifically included in the claims hereto appended.

I claim:

1. The method of producing a die-cast article comprising supporting a wooden core within a die and spaced from the walls thereof, forcing molten die casting metal at a temperature above 1000 degrees F. into the die 75 under such high pressure as to surround the core with a coating of die-cast metal with sufficient rapidity to prevent combustion of the core.

2. As an article of manufacture, a shell of 80 die cast metal having a melting point higher than the combustion point of wood, and a wooden core permanently positioned in said shell in intimate contact therewith throughout the inside surface of the shell.

3. The method of producing a die cast article comprising supporting a wooden core within a die and spaced from the walls thereof, and forcing molten die casting metal at a temperature higher than the combustion 90 point of wood into the die under high pressure.

4. As a new article of manufacture, a shell of die cast metal having a melting point above 1000 degrees F. and a wooden core 95 permanently and wholly enclosed within said shell and having its outside surface in intimate contact with the interior surface of the shell.

In witness whereof I have hereunto set my 100 hand this 6th day of November, 1925.

WILLIAM J. DURING.
